By his Attorney,

J. A. Richards.

UNITED STATES PATENT OFFICE.

GEORGE B. PILKINGTON, OF NEW BRITAIN, CONNECTICUT, ASSIGNOR TO
THE TRAUT & HINE MANUFACTURING COMPANY, OF SAME PLACE.

SUSPENDER-BUCKLE.

SPECIFICATION forming part of Letters Patent No. 462,914, dated November 10, 1891.

Application filed February 26, 1891. Serial No. 382,946. (No model.)

To all whom it may concern:

Be it known that I, GEORGE B. PILKINGTON, a citizen of the United States, residing at New Britain, in the county of Hartford and State 5 of Connecticut, have invented certain new and useful Improvements in Suspender-Buckles, of which the following is a specification.

This invention relates to buckles for suspenders and to that class of suspender-buckles 10 having "cast-offs," the object being to provide a buckle of that class in which the strap-carrying slide shall be connected to the buckle by means of hooks normally held in engagement by a spring, as hereinafter more fully 15 set forth.

In the drawings accompanying and forming a part of this specification, Figure 1 is a front view of a buckle embodying my present invention. Fig. 2 is an edge view of the same 20 as seen from the right hand in Fig. 1. Fig. 3 is a sectional edge view on the line *a a*, Fig. 1. Fig. 4 is a front view of the buckle-plate, which is constructed and furnished for carrying the cast-off slide. Fig. 5 is an edge view 25 of said plate as seen from the right hand in Fig. 4. Fig. 6 is a sectional edge view of the buckle-plate in line *b b*, Fig. 4. Fig. 7 is a front view of the cast-off plate. Fig. 8 is an edge view 30 of the cast-off plate as seen from the right hand in Fig. 7. Fig. 9 is a section of the buckle-plate in line *c c*, Fig. 4. Fig. 10 illustrates a modification of the buckle-plate, whereby this constitutes a part of the buckle-frame.

Similar characters designate like parts in 35 all the figures.

For the purposes of my present improvements the principal part of the buckle is considered to be that which is constructed and 40 furnished for carrying the cast-off slide, and it is immaterial whether, as in Figs. 1 to 9, inclusive, said part constitutes the buckle-lever *L* or whether, as in Fig. 10, said principal part (here designated as *L'*) constitutes a portion 45 of the buckle-frame. The preferred arrangement, however, is shown in Figs. 1 to 9, inclusive, wherein the buckle consists of any ordinary frame, as *F*, having pivoted therein at 2 the upper end of the lever-plate *L*.

The buckle-plate *L* is suitably constructed

at its upper end for attachment to or engagement with the suspender-web, and at the lower end and sides thereof is furnished with the oppositely-disposed guides 4 and 6, between which and said plate there are guide-spaces 8 55 and 10, Fig. 9, for receiving the opposite edges 3 and 5, respectively, of the cast-off slide *S*. The buckle-plate intermediate to said slide-guides has a spring 15, which may be secured to said plate in a well-known manner, (not 60 shown,) but which is preferably and according to one feature of my present improvements formed in said plate, as well shown in Figs. 3, 4, 6, and 9. This spring is for the purpose of holding the slide-plate hooks in 65 engagement with the upper ends 12 and 14 of said guides 4 and 6, respectively.

The cast-off slide *S* is furnished at its lower end with the usual or some suitable means— 70 as, for instance, the opening 7 and the bar 9— for carrying the ordinary suspender-ends. (Not herein shown.) At its upper end and on the opposite sides thereof the cast-off slide has the similar cast-off hooks 16 and 18 for engaging the aforesaid upper guide ends 12 75 and 14 of the buckle-plate *L*. Near the upper end of the cast-off plate, midway of the length thereof, a "button" *B* of a concave or hollow form on the back side thereof is formed in said plate. This button serves as a push- 80 button for detaching the cast-off hooks. The curved upper end 17 of the spring 15 corresponds in position to said concavity, and when the slide-plate is in position, as shown in Figs. 1, 2, and 3, slightly engages the slide- 85 plate in said concavity for the purpose of steadyng the same.

The spaces 8 and 10, Fig. 9, between the buckle-plate *L* and its guides 4 and 6, respectively, are sufficient to allow the free passage 90 of the hooks of the cast-off plate, and consequently when said plate is in position, as in Figs. 2 and 3, there is a considerable space between the buckle-plate and the cast-off plate. As a means for preventing the lateral 95 movement of the cast-off plate in said space, this plate is furnished at its edges with projections or stop-bearings 24 and 26, which fill said guide-spaces at the lower ends thereof, as illustrated in Fig. 3; but said stop-bearings 100

being formed in the slide near the lower ends of the guides and being rounded on the rearward side thereof permit of the necessary rocking movement when the upper end of the slide is pushed back for the unhooking thereof.

In using the buckle to detach the cast-off, the operator has only to press upon the push-button B, thereby forcing back the spring 15 and carrying the cast-off hooks 16 and 18 backward out of engagement with the guides 4 and 6, when the cast-off may be drawn out of said guides. For attaching the cast-off it is only necessary to enter the hook-provided 20 end of the cast-off plate into the spaces between the buckle-plate and its guides and then slide the cast-off plate to its uppermost position, (shown in Figs. 1 to 3,) when the spring throws the hooks forward into engagement with the guides, as there shown.

Having thus described my invention, I claim—

1. In a buckle, the combination, with the buckle-plate having means for the attachment thereof to the suspender-web and having the edges thereof bent forwardly and then inwardly to form the narrow guides 4 and 6, of the strap-carrying slide 8, having the forwardly-projecting hooks 16 and 18 at the upper end thereof, adapted to engage the upper ends of said guides, and a spring on the

buckle-plate and acting against the back side of the slide to hold the same forward into engagement with said guides, the front of the slide between said guides serving as a push-button for detaching said cast-off hooks, substantially as set forth. 35

2. In a buckle, the combination, with the buckle-plate having the slide-guides and the cast-off slide having at the upper end thereof 40 hooks engaging the upper ends of said guides and having a concavity, substantially as described, on the rearward side thereof, of the spring on the buckle-plate and acting upon the slide to hold said hooks in engagement 45 with said guides, said spring also engaging the said concavity, substantially as described.

3. In a buckle, the combination, with the buckle-plate having the slide-guides and the spring, of the slide having the hooks 16 and 50 18 constructed for engaging the upper ends of said guides, the guides being set forward of the buckle-plate sufficiently for the passage of said hooks, and a stop or stops, substantially as described, formed on the slide to stand in the lower part of said guide-spaces, substantially as set forth. 55

GEORGE B. PILKINGTON.
